(57) **CLAIM**

The ornamental design for a child-resistant packaging, as shown and described.

DESCRIPTION

FIG. 1 is a top perspective view of a child-resistant packaging showing our new design in a closed configuration in which the tray component is inside the sleeve component. FIG. 2 is a top plan view thereof.

FIG. 3 is a bottom plan view thereof.

FIG. 4 is a front elevational view thereof.

FIG. 5 is a rear elevational view thereof.

FIG. 6 is a left side elevational view thereof.

FIG. 7 is a right side elevational view thereof.

FIG. 8 is a top perspective view of the child-resistant container of FIG. 1 showing our new design in which the tray component is separated from the sleeve component.

FIG. 9 is a top plan view thereof.

FIG. 10 is a bottom plan view thereof.

FIG. 11 is a front elevational view thereof.

FIG. 12 is a rear elevational view thereof.

FIG. 13 is a left side elevational view thereof.

FIG. 14 is a right side elevational view thereof.

FIG. 15 is a top perspective view of the sleeve component of the child-resistant container of FIG. 1 in an unfolded configuration, shown separately to reveal aspects of the design that may not be apparent in other views.

FIG. 16 is a top plan view thereof.

FIG. 17 is a bottom plan view thereof.

FIG. 18 is a front elevational view thereof.

FIG. 19 is a rear elevational view thereof.

FIG. 20 is a left side elevational view thereof.

FIG. 21 is a right side elevational view thereof.

FIG. 22 is a top perspective view of the tray component of the child-resistant container of FIG. 1, shown separately to reveal aspects of the design that may not be apparent in other views.

FIG. 23 is a top plan view thereof.

FIG. 24 is a bottom plan view thereof.

(Continued)

FIG. 25 is a front elevational view thereof.
 FIG. 26 is a rear elevational view thereof.
 FIG. 27 is a left side elevational view thereof; and,
 FIG. 28 is a right side elevational view thereof.
 The broken lines in the drawings depict fold lines and form part of the claimed design.
